UNITED STATES PATENT OFFICE.

FRED FARRELL, OF CHICAGO, ILLINOIS, ASSIGNOR TO ELECTRICAL ENGINEERS EQUIPMENT COMPANY, OF CHICAGO, ILLINOIS, A CORPORATION OF ILLINOIS.

EXPULSION FUSE.

Application filed March 26, 1925. Serial No. 18,500.

My invention relates to fuses and fuse mountings.

In the use of a fuse of the general type shown in the prior patent to Jacobs #1,503, 5 266, issued July 29, 1924, difficulty is experienced in inserting and removing the fuse from the contacts. The fuse serves the dual function of a disconnect and also a fuse. The blowing of the fuse link opens 10 the circuit and the fuse may then be removed for recharging or replacement. Also the fuse may be pulled out like the blade of a disconnect switch when the circuit is opened as at the oil switch, for rendering 15 the terminal of the oil switch dead.

Heretofore, it has been difficult to remove the fuse from the trunnion bearing because the fuse was loosely mounted in said bearing and was not restrained. According to 20 the present invention I provide a spring stop for the fuse so it will assume a definite angular position where it may readily be seized and removed from the bearing. I have also provided an improved form of 25 eye and catch therefor by which the fuse may be removed from the trunnion bearing without danger of dropping the fuse.

In the blowing of a fuse link, such as is disclosed in said prior patent, there is a 30 tendency for the metal of the link to spatter against the walls of the sleeve and thus lower its insulating value. This is highly objectionable. According to my invention, I provide a jacket for the fuse link which is of 35 such a character as to limit the tendency to spatter fused metal upon the walls of the tube and yet to be sufficiently flexible to be expelled from the sleeve by the explosion of the fuse link. Preferably I employ an 40 asbestos jacket about the link and a porcelain sleeve for the body of the fuse. Obviously, other materials may be employed.

My invention provides other incidental improvements, such as appear in the trunnion bearing and its retaining spring, the cap for the upper end of the fuse body, the stop for the upper end of the fuse body against the upper contact, and other features, all as will appear from the following 50 description, drawings and claims.

While the fuse shown and described is of the expulsion type, it is to be understood that the present construction is also adaptable to fuses of any other type.

In order to acquaint those skilled in the art with the manner of practicing my invention, I shall now describe a particular embodiment of the same in connection with the accompanying drawings.

In the drawings:—

Fig. 1 is a side elevational view of an expulsion fuse mounted in place on its terminal support and brings out the idea of my novel hinge arrangement and, in dotted lines, the manner of removing the fuse out of engagement with the hinge support;

Fig. 2 is an enlarged sectional view setting out in greater detail the features of the hinge arrangement between the fuse and the lower terminal support;

Fig. 3 is an enlarged sectional view of the fuse taken on line 3—3 of Fig. 1;

Fig. 4 is an enlarged sectional view taken on line 4—4 of Fig. 1 and illustrates the novel arrangement of the hinge spring and cams;

Fig. 5 is a sectional view taken on line 5—5 of Fig. 1;

Fig. 6 is a longitudinal sectional view of an expulsion fuse of my invention; and

Fig. 7 illustrates the type of switch stick employed and the manner of using it in disconnecting the fuse from one of its terminal supports.

To a standard base member 10 are secured insulator supports 11 and 12 on which in turn are mounted the insulators 13 and 14. On the tops of these insulators are fitted the metal caps 15 and 16. The character of the insulators and mounting parts 85 is not of the essence of the present invention, and may be of any standard type.

For mounting the fuse terminals to the caps 15 and 16, suitable angle brackets 17 and 18 are provided to which are fastened 95 the terminal members 21 and 22 by bolts 23. One of the contact terminals, designated in its entirety by the numeral 19, is made up of a pair of spring jaws 24, reenforcing plates 25 and arcing springs 26. Suitable 100 openings are provided at the lower ends in all of these members by which they may be fastened to the terminal member 22, by means of bolts 27. The lower contact terminal, which is generally designated by the numeral 20, is likewise provided with a pair of spring jaws 28 and reenforcing members 29. The parts 28 and 29 also have suitable 105

openings at their lower ends by which they may be secured to the terminal member 21 as by the bolts 30. The spring jaws 28 are flared outwardly, thereby serving as guides 5 when the fuse is being replaced. The arcing horns, reenforcing members and the spring jaws for both terminals, are preferably made of copper.

The fuse itself, which is designated as an 10 entirely by the reference numeral 32, comprises a sleeve or tube 33, which may be of any suitable insulating material, such as fiber, bakelite, porcelain, or the like. This tube is provided with block-shaped contact 15 members or ferrules 34 and 35, which are securely fitted to its upper and lower ends respectively. An eccentric flange 36 is cast integral with one end of the block 34. The purpose in making this flange eccentric is 20 to permit it to readily clear the contact jaws and arcing horns. A knurled thumb screw 37 is adapted to fit into a threaded opening in the eccentric portion of the flange 36. An arcuate depression 36^a is provided in the adjacent face of ferrule 34 to accommodate the projecting end portion of screw 37. This thumb screw serves to fasten the fuse wire 38 to the integral flange portion of the contact block. The outside edge of the flange 30 36 is threaded which threads are adapted to cooperate with the internal threads of the cap 39, which serves to properly protect the upper end of the fuse and also to prevent refuse matter and gases to be shot out of this 35 end when the fuse blows. The lower end of the contact block 34 is relatively cylindrical in form, and has on one side a ring 40 which extends out laterally and which serves as a means by which the fuse may be 40 swung into or out of contact with the jaws 24 as shown in Fig. 1. Opposite the integral ring portion 40 is the clamping portion 42, into which is threaded the clamping bolt 43. The central portion of the block 34 45 is hollow so as to permit the fuse 38 to be freely admitted therethrough. That part of the hollow portion which is under the contact surface of the block 34 is relatively rectangular in form. This is also true of the 50 contact portion of the block so as to permit of surface contact between the block and its cooperating contact jaws. From the relatively rectangular form in the contact portion of the block, the hollow portion merges 55 into a relatively circular opening in the clamping end of the contact block. This end is adapted to receive the insulating sleeve 33. In order to insure a tight fit between the tube 33 and the contact block 34, 60 a cushion seal 41, made of braided copper, is inserted therebetween. The insulating tube 33 may be held securely in the clamping member 42 by tightening the bolt 43. The clamping member 42 is also provided 65 with a flange portion 45 which cooperates

with a stop 44 on the terminal member 22 to limit the travel of this end of the fuse toward the terminal member. The stop 44 is secured in place by the bolt 23. By limiting the travel of the fuse or connecting member 32, it also serves to properly position the contact block 34 with reference to the contact jaws 24. Proper contact with the terminal 19 may be had by means of a socketed terminal 46 that is secured to the 75 terminal member 22 by bolts 47.

The lower end of the insulating tube 33 fits into an integral clamping portion 48 of the contact block 35. This clamping portion is also relatively cylindrical in form and is 80 provided with a bolt means 49 by which it may be tightly secured to the tube 33. A cushion seal, however, is also provided between the tube 33 and the inner wall of the clamping means 48 which is also of braided 85 copper. The relatively cylindrical clamping portion 48 merges into a relatively rectangular contact portion 50, which is adapted for cooperative engagement with the contact jaws 28. Centrally located on the upper side of the part 50 is an outwardly projecting lug 51, in which is secured a threaded stud 52. A knurled screw 53 cooperates with the stud 52 to secure thereto the fuse wire 38 which is fastened between the brass washer 54 and the lock nut 55 on the stud 52.

Extending out laterally from the lower square portion of the contact block 35 and integral therewith, is a flat plate member 56 provided with a key-hole opening 31. Portion 50 of block 35 is provided with an arcuate recess or depression 50^a disposed concentric and in alignment with the upper portion of key-hole opening 31, to facilitate insertion of a key member through the opening. It is by means of this opening, as will be explained later, that member 32 may be placed on or removed from its support.

Extending downward from the contacting sides of the portion 50 are the supporting plates 57 and 58. The hollow portion of the contact block 35 extends from the relatively circular hollow portion at the clamping end of the contact block 35 through the rectangular hollow portion in the contact part of the block and out into the space between these supporting plates. This provides an opening 59 at the lower end of the block 35, which permits all refuse matter and gases to be blown out between the supporting plates.

The lower ends of the plates 57 and 58 have pins 60 and 63 projecting from their outer faces and cams 61 and 62 opposite the pins and integral with the inner faces of the plates. The pins 60 and 63 are adapted to engage with the bearing surfaces in the hinge portions of the hook-shaped members 64 and 65 and the springs 66 and 67. The hook-shaped members 64 and 65 have open 130

slot portions 75 and are cast integral with the terminal member 21 and extend outwardly from the opposite sides thereof.

The cams 61 and 62 are adapted to cooperate with a roller member 68 on the pin 69. The pin 69 connects the hook-shaped members 64 and 65. The outer faces of the members 64 and 65 are provided with integral lugs 70 and 71, each of which has an opening therein through which the springs 66 and 67 respectively may be freely admitted. These lugs serve to hold one end of the springs in position, the other end in each case being held in place by the outwardly projecting pins 72 and 73. These pins are also integral with the members 64 and 65, respectively, and have openings therein in which the ends of the springs 66 and 67 may be inserted. From the dotted line view 20 of the springs, as shown in Fig. 2, it will be noted that each of them is provided with a hump portion 74 which bears against the outward projecting end of the pin 63. In so doing, it serves to hold the pin against the 25 bearings in the members 64 and 65 so as to prevent the fuse 32 to work its way out of the slot 75 when it is being swung back into position after renewal.

A spring bumper arm 76 serves to limit 30 the downward travel of the fuse when it is swung out and into open position not only to reduce the impact of the fuse dropped downwardly, but more essentially to hold the fuse in the inclined position shown in dotted 35 lines in Fig. 1 where the keyhole slot 31 will be held definitely in such a position that the operator may easily insert the key 40 84 on the stick 81. Thus the fuse is held definitely in position by its weight tending to rotate it in the counter clockwise direction, as viewed in Fig. 1, and the spring 45 pressure tending to push against it in a clockwise direction, as viewed in Fig. 1. Free swinging of the fuse is thereby prevented and, at the same time, the inclined 50 position of the fuse is most advantageous and suitable for easy coupling of the coupling members 84 and 31. This spring arm is secured to the terminal 21 by means of the 55 bolts 77, which also serves to fasten the connecting socket 78 thereto.

As heretofore mentioned, the fuse wire 38 is surrounded by a jacket of insulating material, such as asbestos, which prevents the 60 metal from spattering up the inner wall of the outer tube when the fuse blows. This jacket, which is designated in the drawings by the numeral 80 rests upon the lower end of the fuse wire and fits rather loosely 65 thereon.

For the purpose of opening, closing or 70 removing the fuse 32 with respect to its 75 terminal supports, I have provided a switch stick 81 having at one end a metal cap portion 82. Integral with this cap portion 82 is

an outward extending pin member 83 and an upwardly extending key member 84. In operation, the member 83 is adapted to cooperate with the hole in the ring 40, to remove the fuse out of the contact terminal 70 19 or to swing it about the lower hinge support into contact with the terminal 19. The pin member 83 has a knob or enlargement at its end which provides a shoulder to keep the pin from slipping out of the 75 eye when the operator pulls upon the handle or pole 81 in the position shown in Fig. 7. Likewise, upon swinging the fuse from its dotted line position in Fig. 1 to its full line position, this knob on the pin 83 keeps the 80 pin from slipping out of the eye too readily. The key member 84 is adapted to cooperate with the key hole opening 31 in the plate 56. To remove the fuse from its mounting, as shown in full line position in Fig. 1, the 85 laterally extending pin 83 of the operating handle 81 is inserted laterally into the ring 40 and then, by a quick downward jerk on the handle 81, the fuse is swung about its trunnions 60 63 into the dotted line position shown in Fig. 1. The buffer spring 76 prevents further rotary movement on the trunnions 60.

Now in order to remove the fuse from its trunnion, it is necessary to push upward 90 95 endwise on the fuse to remove the trunnions out of the open bearings against the holding power of the retaining springs 66 67.

I am aware that heretofore it has been attempted to remove such a fuse from its 100 trunnions by means of an eye member having a transverse opening and located adjacent the trunnion member, such as shown, for example, in the prior patent to Jacobs, No. 1,503,266. The difficulty, however, has been that when the operating stick is pushed upwardly to disengage the fuse from its 105 trunnion, it often jumps off of the pin on the operating stick and falls to the ground and is broken.

The key shaped pin and key hole slot of my invention effectively prevent this. When the fuse has been swung to the dotted line position shown in Fig. 1, the key member 84 is then inserted through the slot 31 and 110 turned by a twisting motion of the stick 81. The key member 84 comprises a central circular shank with a collar or shoulder 85 below it, and with the wing or web extending laterally at the upper end of said round shank. Hence, when the key member is turned on its round shank in the round part of the key hole slot, the web turns out of register with the slot through which it entered, and as a result the stick and the fuse 115 are firmly secured together, so that an upward thrust on the stick pushes the trunnions out of their bearings and even if the fuse does tend to jump upwardly, due to the thrust, it cannot come off of the key 84 120 125 130.

- until the parts are rotated relative to each other to bring the web of the key into register with the slot of the key hole. As a result of this construction, the stick and the fuse are tied together so that the fuse may readily be removed from or replaced into its bearing without danger of the fuse falling off of its supporting stick and becoming damaged by the fall. The only way that the key and key hole can become disengaged is by a rotary and axial movement of such a character as to bring the key and key hole accurately into alignment and then withdraw the key from the key hole.
- 15 To replace the fuse after it has been removed it is only necessary to place it on the switch stick, so that it rests on the collar 85 the key 84 being then turned to move the web out of register with the slot in the key hole 31. It may then be lifted up and placed into the opening 75 and forced past the hump in the springs 74 by means of the key member 84. When the ends of the springs 67 are resting in their bearings in the members 64 and 65, the switch stick may be removed out of the opening 31 and the portion 83 may be inserted in the opening in the ring 40. The fuse may be then swung up and into position as shown by the full lines in Fig. 1.
- 30 I consider that it is broadly new to connect a fuse of this character with an operating stick by means which requires rotary motion of the stick to connect the parts. I further believe that it is broadly new to connect the fuse and the operating stick by means requiring first an axial and then a rotary motion. While the key and key hole slot is highly practical and is the preferred construction, I do not intend to be limited 35 to this manner of forming the connection.
- 40 I do not intend to be limited to the precise details shown or described.
- I claim:—
1. In a device of the class described, a contact block having a screw terminal at one end, a split clamping portion at the opposite end, and a contact portion intermediate said ends, said contact portion having flat sides, said clamping portion having a flat abutment surface extending out laterally and disposed beyond said contact portion.
  2. In a device of the class described, in combination, a terminal member, a pair of contact jaws on opposite sides of said terminal member, a pair of reenforcing plates for said contact jaws, a pair of arcing horns on the outer faces of said reenforcing plates, and bolt means for securing the contact jaws, reenforcing plates and the arcing horns to the terminal member.
  3. In a fuse, a sleeve of vitreous material, a ferrule therefor, said ferrule having at one end a split clamp forming a socket for the end of the sleeve, and a contact portion beyond the clamp providing flat contact sur-

faces, and a yielding pad of metal between the walls of the split clamp and the end of the sleeve.

4. In a fuse, a sleeve of insulation, a ferrule therefor, said ferrule having at one end a split clamp forming a socket for the end of the sleeve, and a contact portion on the ferrule providing flat contact surfaces, said split clamp having an eye at its front side and a stop lug at the opposite side. 70

5. In combination, a contact block having a pair of axially extending legs, transverse trunnions on the ends of said legs, a cam integral with one of said legs, a stationary contact member having bearing supports with bearings adapted to receive the trunnions, a transverse member joining said bearing supports, said cam-cooperating with said transverse member for holding the trunnions in their supports. 80

6. In combination, a contact block having a split clamping portion at one end and a pair of parallel mounting plates at the opposite end, a longitudinal opening in said contact block having a fuse link extending therethrough, and means provided adjacent the contact portion of said contact block for securing said fuse link thereto said link being adapted to be expelled through said opening. 85

7. In combination, a contact block having a clamping portion at one end, and a pair of parallel mounting plates at the opposite end, the lower end of said contact block being open to permit the fused metal to be forced outwardly. 100

8. In combination, a pair of terminal members, a fuse having at one end a contact block provided with an eye having a lateral opening and at its opposite end a contact block provided with an eye having a longitudinal opening, and means adapted to cooperate with the lateral opening and with the longitudinal opening of said eyes for removing said fuse out of contact with 105 said terminal members.

9. In combination, a pair of terminal members, a fuse having at one end a contact block provided with an eye having a lateral opening and at the opposite end a contact block provided with an eye having a longitudinal opening, means adapted to engage with the lateral opening in said first eye for removing said fuse out of contact with one of said terminal members, and means adapted to engage with the longitudinal opening in said second eye for removing said fuse out of contact with the second terminal member by a relatively longitudinal movement of said fuse. 115

10. In combination, a terminal member, a fuse having a contact block provided with an eye having a longitudinal opening, means adapted to engage said opening by relatively longitudinal movement thereof, said means 120

being adapted to be locked in said opening by relative angular motion for removal of said fuse out of contact with said terminal.

11. In combination, a pair of terminal members, a fuse having contact blocks at its opposite ends adapted to cooperate with said terminal members, a ring portion on one of said contact blocks said ring portion having a transverse opening and a portion 10 having a longitudinal keyhole slot on the other contact block, and means adapted to cooperate with the ring on said first contact block and with the keyhole slot in said second contact block for removing said fuse 15 out of contact with said terminal members.

12. In combination, a pair of terminal members, a fuse having contact blocks at its opposite end, a ring with transverse opening integral with one of said contact 20 blocks, a portion having a longitudinal keyhole slot therein on the other contact block, means adapted to engage with said ring for swinging said fuse out of contact with one of said terminal members, and means adapted 25 to engage with the keyhole slot in said portion on said second contact block for removing said fuse out of contact with said second terminal member.

13. In combination, a terminal member, 30 a contact block having a laterally extending portion provided with a longitudinally extending keyhole slot for cooperating with said terminal member, and means adapted to engage with said keyhole slot for moving 35 said contact block into and out of contact with said terminal member.

14. In combination, a terminal member, 40 a contact block having a laterally extending portion provided with a longitudinal opening keyhole slot, means adapted to engage with said keyhole slot for moving said contact block into and out of contact with said terminal member, said means comprising a switch stick having a key member extending 45 longitudinally of the stick.

15. A switch stick having a pair of finger members fastened thereto, one of which extends out laterally and the other longitudinally relative said switch stick said latter 50 finger comprising a key member having a lateral wing at its upper end.

16. A switch stick having a pair of finger members secured thereto, one of which extends out laterally and the other substantially longitudinally, said longitudinally extending finger member terminating in a laterally projecting web portion adapted for locking engagement with a keyhole slot.

17. In combination, a contact block having 60 a pair of outwardly extending plates, bearing pins in the lower extremities of said plates and on the outer sides thereof, a cam integral with one of said plates, a terminal member having supports adapted to receive the bearing pins of said contact blocks, and

means adapted to cooperate with the said cam for positively holding said bearing pins in said support.

18. In combination, a terminal member having a pair of supports, a contact block 70 having bearing pins adapted for pivotal movement in said support, spring means fastened to said support and adapted to cooperate with said bearing pins for constraining the movement of said contact block about 75 said support, and eccentric means for positively holding said contact block in said support.

19. In combination, a terminal member having a pair of supports, a contact block 80 provided with a laterally extending portion having a longitudinally extending keyhole slot therein, bearing pins on said contact block adapted for movement with said supports, means for constraining the movement 85 of said bearing pins in said supports, and key means adapted to cooperate with the keyhole slot in said integral portion for removing said contact block out of said supports against the force of said constraining 90 means.

20. In combination, a terminal member, a contact block adapted for cooperation with said terminal member, a clamping portion for said contact block having a laterally 95 extending flange, an abutment post on said terminal member, said abutment post being adapted to cooperate with said flange for limiting the travel of said contact block in said terminal member.

21. In combination, a pair of insulated spring contacts, open trunnion bearings adjacent one of said contacts, a fuse member having trunnions at its lower end seated in said bearings, said fuse member having contact portions co-operating with said spring contacts, eye members on said fuse adjacent said contact portions, the upper eye member having a transverse opening and being mounted on the front side of said trunnion, 105 and the lower eye member having a longitudinal opening and being disposed on the back side of said trunnion member when the fuse is mounted in the spring contacts.

22. In combination, a pair of insulated spring contacts, open trunnion bearings adjacent one of said contacts, a fuse member having trunnions at its lower end seated in said bearings, said fuse member having contact portions co-operating with said spring contacts, eye members on said fuse adjacent said contact portions, the upper eye member having a transverse opening and being mounted on the front side of said trunnion, 110 and the lower eye member having a longitudinal opening and being disposed on the back side of said trunnion member when the fuse is mounted in the spring contacts, and a buffer member for holding the fuse inclined 120

125 downwardly and outwardly to hold 130

the longitudinal opening in the lower eye member in readily accessible position to be engaged by a longitudinally extending finger for removing the same from the bearings.

- 5 23. In combination, a pair of insulated spring contacts, open trunnion bearings adjacent one of said contacts, a fuse member having trunnions at its lower end seated in said bearings, said fuse member having contact 10 portions co-operating with said spring contacts, eye members on said fuse adjacent said contact portions, the upper eye member having a transverse opening and being mounted on the front side of said trunnion, and the 15 lower eye member having a longitudinal opening and being disposed on the back side of said trunnion member when the fuse is mounted in the spring contacts, and an operating stick having a transversely extending 20 finger for hooking into the first eye to swing the fuse about its trunnions downwardly, and a longitudinally extending finger for co-operation with the lower eye member, said longitudinally extending finger and said lower 25 eye having interfitting parts requiring relative longitudinal and rotary motion to couple the same together.

24. In combination, a pair of insulated spring contacts, open trunnion bearings adjacent one of said contacts, a fuse member having trunnions at its lower end seated in said bearings, said fuse member having contact portions co-operating with said spring contacts, eye members on said fuse adjacent 30 said contact portions, the upper eye member having a transverse opening and being mounted on the front side of said trunnion, and the lower eye member having a longitudinal opening and being disposed on the 35 back side of said trunnion member when the fuse is mounted in the spring contacts, and a buffer member for holding the fuse inclined downwardly and outwardly to hold the longitudinal opening in the lower eye member 40 in readily accessible position to be engaged by a longitudinally extending finger for removing the same from the bearings, and an operating stick having a transversely extending finger for hooking into the first eye to 45 swing the fuse about its trunnions downwardly, and a longitudinally extending finger for co-operation with the lower eye member, said longitudinally extending finger and said lower eye having interfitting parts requiring 50 relative longitudinal and rotary motion to couple the same together.

25. In combination, a fuse having trunnions, stationary bearings for said trunnions open at the top, an operating stick for removing said fuse from its bearings, said fuse and said stick having co-operating and interfitting members requiring relative longitudinal and rotary motion to couple the same together.

- 65 26. The combination of a fuse having a

longitudinal sleeve of insulation, contact members on the ends thereof, and a transversely projecting ring secured to the fuse structure and having a key hole slot therein opening longitudinally of said fuse for 70 reception of an element for removal of the fuse from a support therefor.

27. The combination of a fuse having a longitudinal sleeve of insulation, contact members on the ends thereof, a transversely 75 projecting ring having a key hole slot therein opening longitudinally of said fuse, and an operating stick having a prong provided with a lateral web and being adapted to be projected through the key hole opening in 80 said ring.

28. In combination, a pair of spring terminal members, bearing brackets adjacent one of said members, said brackets having open bearings therein, a fuse having contact 85 portions co-operating with said terminal members and having trunnions adapted to be mounted in said bearings, and an eye adjacent said trunnions, said eye comprising a key hole slot opening longitudinally of 90 the fuse.

29. In combination, a fuse having a sleeve of insulation, metal contact ferrules on said sleeve, one of said ferrules having an eye with a longitudinally extending key hole slot, 95 and a stick having a longitudinally extending prong, said prong having a cylindrical stem with a shoulder below the stem, and a lateral wing formed above the stem, said prong extending through said key hole and 100 said eye being held between said wing and said shoulder.

30. In combination, a fuse having trunnions, stationary bearings for said trunnions open in the direction of the axis of the fuse, 105 an operating stick for removing said fuse from its bearings, said stick and the fuse having cooperating quick acting means for coupling the fuse and the stick together, 110 said means positively preventing detachment 110 of the fuse from the stick when in operative position.

31. In combination, a fuse having trunnions, stationary bearings for said trunnions open at the top, an operating stick for removing said fuse from its bearings, said stick and the fuse having cooperating coupling members requiring relative longitudinal and rotary motion to couple the same 120 together, the completion of the coupling between said members being effected by rotary movement of the stick through less than one complete revolution.

32. In combination, a fuse having trunnions, stationary bearings for said trunnions open in the direction of the axis of the fuse, an operating stick for exerting upward pressure on the fuse for removing it from its bearings, said stick and the fuse having 125 cooperating coupling means acting to pre- 130

vent relative upward movement of the fuse when removed.

33. In combination, a fuse having trunnions, stationary bearings for said trunnions 5 open in the direction of the axis of the fuse, an operating stick for exerting upward pressure on the fuse for removing it from its bearings, yielding means projecting across the tops of the bearings and releasably 10 holding the trunnions against upward movement out of the bearings, the stick and the fuse having cooperating coupling means acting to prevent relative upward movement of the fuse when released.

34. In combination, a fuse having trunnions, stationary bearings for said trunnions open at the top, a buffer below the bearings disposed to support the fuse in open position and at a downward inclination, a stick hav-

ing an operating member extending therefrom, and a member carried by the fuse and disposed for reception of said operating member when the fuse is in open position.

35. In combination, a fuse having trunnions, stationary bearings for said trunnions open at the top, a buffer disposed to support the fuse in open position and at a downward and forward inclination, a member carried by the fuse and disposed forwardly thereof when the fuse is open, and a stick having a 25 member adapted for cooperation with the fuse member for locking the fuse and the stick together when removing said fuse from its bearings.

In witness whereof, I hereunto subscribe 30 my name this 23rd day of March, 1925.

FRED FARRELL.
